ILLUMINATING DEVICE FOR HANDBAGS

Earl W. Burns, Urichsville, Ohio

Application October 4, 1939, Serial No. 297,952

3 Claims. (Cl. 240—6.45)

This invention relates to illuminating devices, and its general object is to provide a device in the form of an attachment primarily designed for ladies' handbags and the like, for illuminating the interior thereof, the device acting in the capacity of a flashlight, but is constructed and associated with the bag in a manner whereby the device is automatically illuminated upon the opening of the bag and extinguished when the bag is closed.

A further object is to provide an illuminating device for handbags and the like, that is simple in construction, inexpensive to manufacture, can be easily removed and applied with respect to the bag, and it is extremely efficient in operation, use and service.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing where-in like characters denote like or corresponding parts throughout the several views, and in which:

Figure 1 is a perspective view illustrating my device within a handbag and the position assumed by the bulb carried switch means for rendering the same active, to illuminate the bag when open.

Figure 2 is an end view of the bag illustrating the device in dotted lines and the position assumed by the bulb carried switch means for extinguishing the same when the bag is closed.

Figure 3 is a sectional view taken through the bag and the device mounted therein, with parts in elevation.

Figure 4 is a longitudinal sectional view taken through the bulb carried switch means of my device with parts in elevation.

Referring to the drawing in detail, the letter A indicates a lady's handbag having the usual pivoted two part frame for the mouth thereof, a catch for securing the mouth in closed position, and handles secured to the frame, all of which form no part of the present invention which lies solely in the illuminating device for the interior of the bag.

The illuminating device includes a bulb carried switch means constructed to provide a body in the form of a cylindrical housing 1 having one end closed by a wall 2, and the opposite end may be open as shown, but in any event is preferably

beveled as at 3 to follow the inclination of a side wall of the bag, as clearly shown in Figures 2 and 3. Mounted for slideable movement in the housing 1 and in loose fitting association therewith, is a relatively thick disk like block 4 of insulating material having a headed contact member 5 extending centrally therethrough, as clearly shown in Figure 4.

The housing is provided with diametrically opposed slots 6 extending longitudinally thereof for a portion of its length and disposed within and through the slots are the inturned ends of arms 7 of a bail shaped pull element that includes a loop providing an eye 8 in the bight portion thereof, as clearly shown in Figure 4. The inturned ends provide trunnions 9 journaled in the block 4 for moving the same against the action of a coil spring 10 sleeved about a threaded socket 11 fixed to and extending inwardly from the wall 2 for receiving the shank of a flashlight bulb 12, the spring engaging the wall 2 and the block for normally holding the head of the contact member 5 spaced from the contact member 13 of the bulb, but it will be obvious from Figure 4 that a pulling action upon the bail shaped element will result in the head engaging the contact member 13 for closing the circuit to the bulb.

The bulb carried switch means is detachably secured within the handbag in a manner to bridge the front and rear walls thereof, and for that purpose, the housing has secured to the open end thereof a right angled disposed pin member 14 and a catch 15 for the pin member to connect that end of said means to the lining of one wall, while the opposite end is connected to the lining 25 of the other wall by an elastic strand 16 having its ends connected respectively to an eye 8 and a safety pin 17.

A shade 18 may be provided for the bulb for directing the rays of light therefrom downwardly within the bag, as indicated in Figure 1, and the shade includes a reduced attaching portion fixed to the wall 2 in any suitable manner, for the disposal of the body of the shade about the bulb.

The battery casing for my device, is best shown in Figure 3, and includes a cylindrical body 19 having threaded secured to the ends thereof caps 20 and 21 respectively, the cap 20 having secured to its inner face, a ring 22 of insulating material, while the cap 21 has a disk 23 of insulating material secured to its inner face.

The battery casing is of a size to receive the usual pencil type batteries 24, and threadedly mounted in the cap 20 is a headed screw 25 en-

gageable with the central contact member of one of the batteries, to act as a manual switch for opening and closing the circuit to the bulb carried switch means, through the medium of conductors 26 and 27. The conductor 26 has one end fixed to the contact member 5 and its opposite end to a headed contact member 28 centrally disposed within the disk 23 in the path of the base electrode of the other battery, as shown in Figure 3, while the conductor 27 has one end fixed to the housing 1 and its opposite end to the cap 21.

I preferably provide a strip of material 29 having its ends secured to the opposed walls of the handbag, as indicated in Figure 1, to provide a pocket for receiving the battery casing, to hold the same at one end of the bottom of the handbag and therefore in an out of the way position, as will be apparent.

From the above description and disclosure of the drawing, it is believed that the operation of my device will be obvious, but it might be mentioned that when the handbag is closed, as shown in Figure 2, the parts of the bulb carried switch means are in normal position or in other words, the coil spring 10 holds the contact member 5 in spaced relation with respect to the contact member 13, thus the circuit to the bulb is open. However, when the bag is opened, the block 4 is directed toward the bulb against the action of the coil spring 10 for disposing the contact member 5 in engagement with the contact member 13, and thereby closing the circuit for illuminating the bulb and consequently the interior of the bag. It is of course understood that the manual switch which includes the headed screw 25 is closed at all times, during the use of the bag.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:

1. An electric illuminating device for a lady's handbag including opposed walls movable toward and away from each other upon closing and opening said bag, and comprising a housing having a closed end, means secured to the opposite end for detachably connecting the housing to one of said walls, a light bulb mounted in and electrically connected to the closed end, switch means for the light bulb and engageable with the contact means thereof, a spring between the closed end and the switch means for normally holding the latter spaced from the contact

means, a source of current in circuit with the housing and the switch means, means for connecting the switch means to the other wall and including a bail like member having trunnions mounted in the switch means, and elastic means connected to the bail like member.

2. An electric illuminating device for a lady's handbag including opposed walls movable toward and away from each other upon closing and opening said bag, and comprising a substantially cylindrical housing having one end thereof closed and the other end beveled, pin means secured to the beveled end for detachably connecting the housing to one of said walls, a socket extending inwardly from the closed end, a light bulb mounted in the socket, a block of insulating material fittingly mounted within the housing for slidable movement, contact means carried by the block and engageable with the contact means of the bulb, a coil spring between the closed end and the block for normally holding the contact means of the latter spaced from the contact means of the bulb, a source of current in circuit with the housing and the contact means of the block, a bail shaped member including trunnions mounted in the block, elastic means connected to the bail shaped member, and a pin for attachment to the other wall and connected to the elastic means.

3. An electric illuminating device for a lady's handbag including opposed walls movable toward and away from each other upon closing and opening said bag, and comprising a substantially cylindrical housing having a closed end and a beveled end, pin means secured to the beveled end for detachably connecting the housing to one of said walls, a light bulb mounted in the closed end, a shield for the light bulb, a block of insulating material slidably mounted in said casing and the latter having diametrically opposed slots extending longitudinally thereof, a contact member carried by the block and engageable with the central contact member of the bulb, a coil spring between the closed end and the block for normally holding the contact member of the latter spaced from the bulb contact member, means for moving the block against the action of the spring for disposing the block contact member in engagement with the bulb contact member, means for detachably securing said block moving means to the other wall, a casing for disposal within the bag, batteries within said casing, a conductor connected to the block contact means and the batteries, a conductor connected to the casing and the housing, and a manually operated switch mounted in the casing for controlling the circuit to the conductors.

EARL W. BURNS.
